UNITED STATES PATENT OFFICE.

WILLIAM H. STURGEON, OF BEN AVON, PENNSYLVANIA.

DESIGN FOR AN AUTOMOBILE-HEADLIGHT LENS.

55,337.

Specification for Design.

Patented May 25, 1920.

Application filed September 24, 1919. Serial No. 326,085. Term of patent 3½ years.

To all whom it may concern:

Be it known that I, WILLIAM H. STURGEON, a citizen of the United States, residing at Ben Avon, in the county of Allegheny and State of Pennsylvania, have invented a new, original, and ornamental Design for Automobile-Headlight Lens, of which the following is a specification, reference being had to the accompanying drawing, forming a part thereof.

The figure is a front elevation showing my new design.

I claim:

The ornamental design for an automobile headlight lens, as shown.

WILLIAM H. STURGEON.
